UNITED STATES PATENT OFFICE.

WILBER J. HALL, OF PHILADELPHIA, PENNSYLVANIA.

VENDING-TRAY.

1,173,506.

Specification of Letters Patent. Patented Feb. 29, 1916.

Application filed June 11, 1915. Serial No. 33,427.

To all whom it may concern:

Be it known that I, WILBER J. HALL, a citizen of the United States, residing at Philadelphia, county of Philadelphia, and State of Pennsylvania, have invented certain new and useful Improvements in Vending-Trays, of which the following is a specification.

My invention relates to trays and particularly to trays adapted for use in vending eatables in public places, such as railway depots, trains, ball parks and the like.

More specifically my invention relates to vending trays especially adapted for use in vending ice cream cones in places of the character mentioned.

The primary object of my invention is to provide a tray for the purpose mentioned which will preserve the cones, after being filled for sale, for extended periods of time.

A further object of my invention is to provide a tray of the character mentioned which will effectively protect the articles from dust, dirt and cinders and at the same time present the articles to view in an attractive manner.

A further object of my invention is to provide a dispensing tray of the character stated having a lid or closure of such construction that the closure may be held in open position by the hand supporting the device so as to leave the other hand of the dispenser free to remove the articles from the tray, to collect the price, to make change, etc.

A further object of my invention is to provide a device as mentioned which will effectually prevent the articles to be vended from coming in contact with the persons or clothing of the persons patronizing the place of sale.

Further objects of my invention is to provide a device of the character mentioned which may be readily kept clean and also to provide means for holding the closure or closures in open position without manually supporting the same while filling the device for use.

Other objects will appear hereinafter.

With these objects in view my invention consists generally in a comparatively shallow tray with a housing supported above the same so as to exclude free access of air to the casing and tray and means for sup-

porting the articles to be vended within the same.

My invention further consists in a device as mentioned further characterized by having the housing formed of transparent material such as glass and equipped with a closure, preferably hinged whereby access may be readily had to the interior thereof for removing the articles.

My invention further consists in providing a device characterized as above stated with an arched handle, in hingedly mounting the closures and equipping the closures with handles, which when the closures are raised, are in position to be grasped by the fingers of the hand holding the arched handle.

My invention further consists in a dispensing tray as above stated further equipped with means upon the arched supporting handle for holding the closures in raised position during the process of filling the device, said means being preferably removable from the handle when not in use.

My invention further consists in various details of construction and arrangement of parts all as will be fully described herein-after and particularly pointed out in the claims.

My invention will be more readily understood by reference to the accompanying drawings, forming a part of this specification and in which—

Figure 1 is a perspective view of a vending tray embodying my invention, Fig. 2 is a vertical longitudinal section of the same, Fig. 3 is a horizontal section taken through the housing and with portions being broken away to better illustrate the construction, Fig. 4 is a perspective view of the housing removed from the tray proper and illustrating the closures in raised position, and Fig. 5 is a detail perspective view illustrating the preferred form of the means for holding the closures in raised position during the process of filling the device.

Referring now to the drawings, 1 indicates the tray proper which constitutes the bottom of the device and which comprises a hollow body preferably of sheet metal, and open at the top. The tray 1 is comparatively shallow and consists of the bottom 2, side walls 3 and end walls 4. Arranged upon the inner faces of the walls 3

and 4, slightly below the upper edges thereof is a continuous, preferably substantially horizontal flange 5 adapted to support the housing hereinafter described. In order to 5 reinforce the flange and to facilitate cleansing the device a reinforcing angularly disposed portion 6 is formed on the flange, the upper edge of which is flush with the inner edge of the flange 5 and the lower edge of 10 which is secured to the adjacent walls 2 and 3 below the flange as shown in the drawing. Preferably the flange 5 and reinforcing portion 6 are formed of a single strip of sheet metal bent into V-form and having 15 the free edges thereof soldered or otherwise secured to the walls of the tray. With this construction it is obvious that the tray may be quickly and thoroughly rinsed and by tilting the same all of the wash water will 20 be discharged as it is impossible for any portion thereof to lodge beneath the flange. The tray 1 is equipped with an arched, centrally disposed handle 7 to facilitate carrying 25 the device.

8 indicates the housing which preferably comprises a skeleton metal frame having side and end panels formed of glass or similar transparent material and a transparent top closure, the bottom being open. The housing 30 is of a length and breadth slightly less than the corresponding inner dimensions of the tray 1 so that the lower edges thereof may rest upon the flanges 5.

9 indicates the skeleton frame formed of 35 metal channel strips and 10—10 indicate the side and end panels of glass having their edges arranged within the channeled frame members. Centrally of the sides of the housings are a pair of ears 11 formed on supporting strips 12 secured to the frame members 9, and extending transversely across the housing between the ears 11 is a hinge pin or rod 13. Hingedly mounted upon the rod 13 are a pair of closures consisting of skeleton frames 14 and glass panels 15. The frames 14 are formed with depending flanges 16 which fit snugly over the upper edges of the frame 9 when the closures are in lowered or closed position. Each of the 40 hinged closures is provided with a handle 17 to facilitate raising the same. These handles are preferably arranged at the center of the free outer edge of the closure and the distance from the hinge pin 11 to said handles is preferably substantially the same as 45 the distance from the hinge pin to the center of the arched handle 7, so that when said closures are raised the handles 17 may be held by the fingers of the hand grasping the 50 handle 7.

To hold the closures in open position during the process of filling without necessitating manually holding the same, I provide a 55 split ring 18 which is adapted to encircle the handles 7 and 17 as shown in Fig. 5. It is

obvious that when not in use the split ring may be readily removed from the device.

Arranged within the housing is an article supporting member 19 which, when the device is intended for vending ice cream cones, 70 comprises a horizontal member provided with a plurality of openings 20 to receive the ends of the cones as shown in the drawings. This member is preferably supported by angle plates or brackets 21 fixed to the lower members 9 of the frame at the corners. See 75 Figs. 3 and 4. The member 19 is preferably a sheet metal plate provided with the openings 20 and the edges of the plate surrounding said openings are preferably upset 80 forming annular depending flanges 22 to prevent injury to the cones.

From the above description it is obvious 85 that ice cream cones placed within the device will be kept in salable condition for extended periods of time, even in warm weather and close atmospheres. This is particularly desirable when vending cones at railway depots as the cones may be prepared in advance of the arrival of a train and will remain in condition even though the train may be considerably late in arriving. Also the housing fully protects the cones or any other material therein from becoming contaminated by dust, cinders or other foreign matter. 90 It should also be noted that the housing rests loosely between the upper ends of the side and end walls so that the same may be readily removed to permit cleaning of the device; however, on account of the continuity of the flange 5 air is excluded from 100 entering between the side walls of the tray 1 and the lower portion of the housing. With the construction set forth additional refrigerant is not necessary to keep the cones in 105 condition for a reasonable length of time as the frozen cream is sufficient to lower the temperature within the device to a sufficient degree for this purpose as all air is excluded except when the closures are momentarily 110 raised to remove a cone.

I claim:—

1. A vending tray comprising a shallow lower member provided with an upwardly projecting handle, a housing open at the bottom and having its open lower portion fitting within the upper part of said lower member, a hinged closure for the top of said housing, a handle on said closure, said handle when said closure is in raised position, 115 being in proximity to the first said handle whereby both of said handles may be grasped simultaneously with one hand, substantially as described.

2. A vending tray comprising a shallow 125 lower member open at the top, a horizontally disposed flange arranged upon the inner faces of the walls of said lower member adjacent the upper edge thereof and provided with a downwardly inclined re- 130

inforcing portion extending from the free edge of the flange and having its lower end secured to the walls of said bottom member beneath said flange and a housing resting upon said flange, substantially as described.

3. A vending tray comprising a shallow lower member open at the top, supporting members within said lower member, a housing resting upon said supporting members and comprising a skeleton frame and transparent panels, the top of said housing comprising a pair of transparent hinged closures, substantially as described.

4. A vending tray comprising a bottom member open at the top and a handle arranged centrally thereof and spanning the same, a housing open at the bottom and having its lower portion resting within said bottom member, said housing being open at the top, a pair of closures for the open upper end of said housing, said closures being hinged adjacent said handle, and a handle on each of said closures adapted to swing into position adjacent the first said handle when said closures are raised, substantially as described.

5. A vending tray comprising a bottom member open at the top and a handle arranged centrally thereof and spanning the same, a housing open at the bottom and having its lower portion resting within said bottom member, said housing being open at the top, a pair of closures for the open upper end of said housing, said closures being hinged adjacent said handle, a handle on each of said closures adapted to swing into position adjacent the first said handle when said closures are raised, and means on the first said handle for engaging the handles on the closures, substantially as described.

6. A vending tray comprising a bottom member open at the top and a handle arranged centrally thereof and spanning the same, a housing open at the bottom and having its lower portion resting within said bottom member, said housing being open at the top, a pair of closures for the open upper end of said housing, said closures being hinged adjacent said handle, a handle on

each of said closures adapted to swing into position adjacent the first said handle when said closures are raised, and a detachable member adapted to be positioned on the first said handle and to engage the handles on the closures when the latter are in raised position, substantially as described.

7. A vending tray comprising a bottom member open at the top and a handle arranged centrally thereof and spanning the same, a housing open at the bottom and having its lower portion resting within said bottom member, said housing being open at the top, a pair of closures for the open upper end of said housing, said closures being hinged adjacent said handle, a handle on each of said closures adapted to swing into position adjacent the first said handle when said closures are raised, and a split ring adapted to encircle all of said handles simultaneously, substantially as described.

8. A vending tray for ice cream cones comprising a bottom member provided with a supporting flange within the same, a transparent housing open at the bottom and resting upon said flange, an opening in said housing, a closure for said opening, and means within the lower portion of said housing for supporting a plurality of cones, substantially as described.

9. A vending tray for ice cream cones comprising a bottom member provided with a supporting flange within the same, a transparent housing open at the bottom and resting upon said flange, an opening in said housing, a closure for said opening, brackets at the lower edge of said housing and a horizontally disposed plate resting upon said brackets and provided with apertures to receive a plurality of ice cream cones, substantially as described.

In testimony whereof I have signed my name to this specification in the presence of two subscribing witnesses.
